UNITED STATES PATENT OFFICE.

HOSEA WEBSTER, OF MONTCLAIR, NEW JERSEY.

FURNACE.

No. 818,588.

Specification of Letters Patent.

Patented April 24, 1906.

Application filed October 2, 1905. Serial No. 280,928.

To all whom it may concern:

Be it known that I, HOSEA WEBSTER, a citizen of the United States, residing at Montclair, in the county of Essex and State of New Jersey, have invented certain new and useful Improvements in Furnaces, of which the following is a specification, reference being had therein to the accompanying drawings.

10 This invention relates to furnaces for burning solid fuel, and is embodied for illustration in a furnace adapted for steam-boilers.

Figure 1 of the drawings is a side elevation, partly in section; and Fig. 2, a transverse vertical section of the furnace-chamber on the line $x-x$, Fig. 1.

The drawings represent a type of land boiler containing horizontal inclined water-tubes 1, a longitudinal steam and water drum connected through headers 2 3 and circulating-pipes 4 5, with the horizontal steam and water drum 6, the heated gases being compelled to make a plurality of passes through and among the tubes by the transverse baffles 7 8 and passing thence through a down-take 9 to an opening 9² at the base of the boiler-setting connected with the chimney. In this class of boilers the location of the baffles 7 and 8 is conventionally such as to apply 25 portion the length of the tubes between the three passes a , b , and c in such manner as experience has shown to be most efficient, and it has also been customary to locate the bridge-wall bounding the fire at the rear substantially beneath the deflector 7, which separates the first and second passes, or, in other words, so that the front of the bridge-wall was substantially in the position of the dotted line x .

40 The object of my invention is while retaining the general features of the boiler above referred to to obtain greater capacity whereby low grades of fuel may be burned, if desired, and a thorough and complete combustion may be effected.

The various features of my invention will appear from the following description and the appended claims.

Bridge-wall 10, bounding the rear of the furnace-chamber, is set back from the ordinary position (indicated by the dotted line x) to substantially the position shown in the drawings, and the top of it is connected by the roof 11, of fire-brick, to the bottom of the deflector 7. Thus in addition to the ordinary fire-box d (roofed by the water-tubes of the

first pass a) I provide a fire-box extension e , separated from the second pass b by the roof 11 and closed at its rear end by the wall 10.

The gases formed in the fire-box extension e beneath the second pass b can only reach said second pass through the first pass a . They are thus compelled to pass forward (counter-current) to the direction of the air-shaft beneath the grate and are held down by the roof 11 close to the fuel of the grate on their way to the fire-box proper, d , wherein they join the gases coming upward from the fuel in the fire-box proper, wherein the combined gases of the fire-box proper and fire-box extension are equably applied to the area of the tubes in the first pass.

In the form shown both the roof 10 and the grate 13 are upwardly inclined from the rear toward the front 12, and the grate shown 75 is of the shaking type with a dumping section at its inner end. These features combine to increase the efficiency of the fire-box extension e because the inclination of the grate and the agitation of the coal produced by movement thereof constitute a rearwardly-feeding grate and tend to cause the fuel to settle toward the rear of the fire-box extension and compelled to travel forward over the bed of fuel, as above described. In the form shown 80 also the roof 11 is made in the form of an arch, so that its reverberating effect will be brought to bear upon the gases in their passage forward beneath such roof. The upward inclination of the roof 11 and the water-tubes 90 from the rear to the front being at a greater angle than the upward inclination of the grate 13, the combustion-chamber above the grate gradually enlarges, so as to permit of the expansion of the gases in their passage 95 toward the first pass through the tubes.

I claim as my invention--

1. In combination with a steam-boiler of the horizontal inclined water-tube type having a plurality of passes for the gases through the tubes and a fire-box roofed by the tubes of the first pass, a rearward extension of said fire-box beneath the second pass, a grate extending through said fire-box and said extension; a roof separating said extension from said second boiler-pass, and a wall closing said fire-box extension at the rear.

2. In combination with a steam-boiler of the horizontal inclined water-tube type having a plurality of passes for the gases through the tubes and a fire-box roofed by the tubes of the first pass, a rearward extension of said

fire-box beneath the second pass, a rearwardly-feeding grate extending through said fire-box and said extension and a roof separating said extension from said second boiler-pass.

3. In combination with a steam-boiler of the horizontal inclined water-tube type having a plurality of passes for the gases through the tubes and a downtake at the rear of the boiler and a fire-box roofed by the tubes in the first pass, of a bridge-wall located between the medial line of said water-tubes and

said downtake; a roof extending forwardly from the top of said bridge-wall to the first pass, and a grate extending from the front of the boiler to said bridge-wall throughout the space roofed by the tubes of the first pass, and said roof.

In testimony whereof I affix my signature in presence of two witnesses.

HOSEA WEBSTER.
